US0D1107693S

(12) **United States Design Patent** (10) **Patent No.:** **US D1,107,693 S**
(45) **Date of Patent:** **** Dec. 30, 2025**

(54) **ELECTRONIC DEVICE**

(71) Applicant: **Apple Inc.**, Cupertino, CA (US)

(72) Inventors: **Jody Akana**, Los Altos Hills, CA (US); **Bartley K. Andre**, Los Gatos, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, Lake Forest, IL (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/978,669**

(22) Filed: **Dec. 13, 2024**

Related U.S. Application Data

(63) Continuation of application No. 29/858,379, filed on Oct. 31, 2022, now Pat. No. Des. 1,054,415, which is a continuation of application No. 29/704,606, filed on Sep. 5, 2019, now Pat. No. Des. 968,393, which is a continuation of application No. 29/605,524, filed on May 26, 2017, now Pat. No. Des. 859,397, which is a continuation of application No. 29/562,315, filed on Apr. 25, 2016, now Pat. No. Des. 788,104, which is a continuation of application No. 29/557,222, filed on

Mar. 7, 2016, now Pat. No. Des. 778,904, which is a continuation of application No. 29/489,530, filed on Apr. 30, 2014, now Pat. No. Des. 751,064, which is a continuation of application No. 29/454,126, filed on May 7, 2013, now Pat. No. Des. 705,779, which is a continuation of application No. 29/429,478, filed on Aug. 11, 2012, now Pat. No. Des. 681,632.

(57) CLAIM

The ornamental design for an electronic device as shown and described.

DESCRIPTION

FIG. 1 is a bottom front perspective view of an electronic device showing the claimed design;
 FIG. 2 is a bottom rear perspective view thereof;
 FIG. 3 is a top rear perspective view thereof;
 FIG. 4 is a front view thereof;
 FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the figures show portions of the electronic device that form no part of the claimed design.
